UNITED STATES PATENT OFFICE

2,689,370

HINGE AND SUPPORT FOR CEDAR
CHEST LIDSRoy A. Stone, Rockford, Ill., assignor to National
Lock Company, Rockford, Ill., a corporation of
Delaware

Application September 14, 1949, Serial No. 115,580

3 Claims. (Cl. 16—163)

1

The present invention relates to a novel counter-balancing hinge and pivotal support particularly adapted for pivotally mounting and supporting the lid of a cedar chest or the like in any desired elevated position.

One of the disadvantages found in cedar chests of the type now in general use, is that the lid must be held in open, elevated position unless the chest is withdrawn or located sufficiently away from the wall to permit the lid to tilt rearwardly of a vertical plane. Thus either the chest must be placed a substantial distance from the wall or moved away therefrom when access is to be had requiring the lid to be held open, otherwise the person gaining access thereto must hold the lid to maintain it open.

Another disadvantage inherent in the present commercial types of cedar chests is in the manner of pivotally mounting the lid whereby the lid when moved to open position swings rearwardly of its pivotal mounting or hinge assembly, and in order to prevent marring or damage to the wall the chest must be positioned a substantial distance away from the wall.

The objections or disadvantages are completely obviated in the present invention for not only is the lid held counterbalanced in any partially open or fully open position, but the top of the lid swings inwardly in opening and when fully open the top of the lid is vertically aligned with the rear of the cedar chest.

It is, therefore, an important object of the present invention to provide a novel hinge assembly at the rear of and connecting the chest and lid which is so constructed and arranged as to mount and support the lid in such manner that in its pivotal movement to open or closed position the lid does not extend beyond or rearwardly of the chest.

A further object of the present invention is the provision of a novel counterbalancing hinge construction for pivotally mounting and supporting the lid of a cedar chest or other suitable container in partially open or fully open position. In the novel illustrative embodiment the lid when opened to a desired position for securing access to the interior thereof is retained in such position and counterbalanced whereby to prevent injury to a person desiring access thereto.

The present invention further comprehends the provision of a novel three-part hinge assembly in which the parts are so related, combined and mounted at the exterior and rear of the chest and lid that the hinge may be disposed flush against or abutting the wall, and the lid when opened is swung forwardly and inwardly therefrom rather than rearwardly and outwardly as in prior constructions.

The invention further resides in the construc-

2

tion, combination and arrangement of parts illustrated in the accompanying drawing, and while there is shown therein a preferred embodiment, it is to be understood that the same is susceptible of modification and change, and comprehends other details, arrangements of parts, features and constructions without departing from the spirit of the invention.

In the drawing:

10 Figure 1 is a view in perspective of a cedar or other chest of the type to which the novel hinge assembly may be applied.

15 Fig. 2 is a disassembled view in perspective of the hinge elements going to make up the novel hinge assembly and their relationship.

20 Fig. 3 is a fragmentary enlarged view in vertical cross-section through the rear of the closed lid and chest, and showing in end elevation the position of the counterbalancing hinge and swivelled lid arm when the lid is in closed position.

25 Fig. 4 is a fragmentary enlarged view similar to Fig. 3, but with the lid in partially open position and with the vertical section taken through the hinge assembly to more clearly disclose its associated parts or hinge elements.

30 Fig. 5 is a view similar to Fig. 4 but with the lid in fully open position and showing how the top of the lid is disposed in vertical alignment with the rear of the chest.

Referring more particularly to the disclosure in the drawing and to the novel illustrative embodiment therein shown, the present invention relates to a novel counterbalancing hinge construction applied to and pivotally mounting and counterbalancing the lid 1 of a cedar chest or the like 2. The lid is shown connected to the chest by a lid arm 3 disposed closely adjacent the interior of the end walls of the lid and chest and which may have one end pivotally connected or swivelled at 4 to an anchoring plate 5 secured

40 to the lid 1, and the other end pivotally connected or swivelled at 6 to an anchoring plate 7 on the interior of the end wall of the chest 2. If desired, these plates 5 and 7 may be omitted and the lid arm 3 may be pivotally connected directly to the lid and chest.

45 The novel hinge assembly of the present invention comprises a chest wing 8 rigidly secured or attached to the rear and exterior of the cedar chest 2 by screws or other attaching means 9, an outside lid wing 11 and an inside lid wing 12 attached to the rear and exterior of the lid 1 by screws or other attaching means 13. To facilitate assembly of the three hinge elements of wings 8, 11 and 12, the opposite sides 14 of the chest wing 8 are each provided with an upwardly projecting ear 15 having an opening 16 there-through, the spaced ears being adapted to receive therebetween the curled end 17 of the outside lid

wing 11. A hinge pin 18 projecting through the openings 16 and the curled end 17 provides a pivotal connection between the chest wing 8 and the outside lid wing 11.

Spaced opposite sides 19 at the upper end of the outside lid wing 11 are each provided with a lateral opening 21 and with these spaced sides adapted to receive therebetween projecting ends or ears 22 of the spaced opposite sides 23 of the inside lid wing 12. A hinge or pivot pin 24 is adapted to be received in the lateral openings 21 in the outside hinge wing 11 and in the aligned lateral openings 25 in the ends or ears 22 of the inside lid wing 12 whereby to pivotally connect these wings or hinge elements. A coil spring 26 encompasses the hinge or pivot pin 24 between the ends or ears 22 and has one end bearing or seating against the web of the outside lid wing 11 and the other end, engaging or bearing against the web of the inside lid wing 12 whereby to effect a counterbalancing action in which the lid 1 is maintained in any desired open position, either partially open, as in Fig. 4 or in fully open position as in Fig. 5. When in this fully open position, the outside lid wing 11 seats upon the upper edge of the chest and the normally rear edge of the lid seats upon the spaced embossments 27 on the then upper surface of the outside lid wing or hinge element 11.

With the novel construction and arrangement of the three-part hinge assembly with one part or chest wing, 8 secured to the exterior of the chest, another part or inside lid wing 12 secured to the exterior of the lid, and a third part or outside lid wing 11 pivotally connecting the other two, the lid when being raised moves inwardly whereby the rear thereof swings inwardly in the manner shown in Fig. 4. When moved to fully open position as shown in Fig. 5, the top of the lid is disposed in vertical alignment with the rear or back of the chest.

From the foregoing and the disclosure in Figs. 3, 4 and 5, it will be seen that the lid at no time during its elevation projects rearwardly of the chest or the fixed hinge wing, 8 secured to the chest, whereby the chest may be placed against or closely adjacent the wall and the lid is maintained out of contact therewith during its swinging movement from closed to fully open position. By this construction, combination and arrangement of the hinge elements and the counterbalancing spring 26, the hinge moves the lid inwardly and retains it counterbalanced in any partially open or fully open position, and when the lid is fully open, the top surface thereof is substantially vertically aligned with the rear of the chest.

Although the various views of the drawing show but a single hinge applied to the cedar chest, it will be understood that generally two of such hinges in suitably spaced relation are required to pivotally mount and support the lid.

Having thus disclosed the invention, I claim:

1. A pivotal support and double acting spring hinge for pivotally mounting a lid on a chest and maintaining the lid counterbalanced when in partially open or fully open position, comprising an arm pivotally connecting the lid to the chest, a hinge member adapted to be secured to the rear of the chest, a hinge member adapted to be secured to the rear of the lid, an intermediate hinge member pivotally connected to the upper end of the chest hinge member and to the adjacent end of the lid hinge member, and provided with spaced sides adapted to receive therebetween the lid hinge member; and a coil spring encompassing

the pivotal connection between the lid hinge member and the intermediate hinge member and having one end engaging the lid hinge member and the other end the intermediate hinge member for spring-biasing said lid hinge and intermediate hinge members to open position, said lid hinge member when the lid is in closed position being confined within the sides of the intermediate hinge member and when the lid is moved to partially or fully open position the lid and intermediate hinge members are spring-biased to open and extended position and moved forwardly from the rear of the chest.

2. A hinge and support for the lid of a cedar chest and the like, comprising an arm pivotally connecting the lid to the chest, a hinge wing adapted to be attached to the rear of the chest, a hinge wing adapted to be attached to the rear of the lid, a hinge member pivotally connected at its opposite ends to the chest and lid hinge wings respectively to provide a pivotal connection therebetween, said hinge member provided with spaced sides adapted to receive therebetween the lid hinge wing when the lid is closed, and a counterbalancing spring having its opposite ends engaging the lid hinge wing and hinge member respectively, the spring and lid hinge wing being confined beneath the hinge member when the lid is closed and when the lid is open the lid hinge wing and hinge member are extended and disposed along the rear of the lid and the lid is supported thereon, said arm, hinge wings, connecting hinge member and spring being so constructed and arranged as to move the lid upwardly and forwardly as it is raised to open position and maintain the lid counterbalanced in any desired partially or fully open position.

3. A pivotal support and double acting spring hinge for pivotally mounting a lid on a chest and maintaining the lid counterbalanced when in open position, comprising an arm pivotally connecting the lid to the chest, a hinge member adapted to be secured to the rear of the chest, a hinge member adapted to be secured to the rear of the lid, an intermediate hinge member pivotally connected to the chest and lid hinge members and movable relative thereto but adapted to receive and enfold the lid hinge member when the lid is closed, said intermediate hinge member having spaced side walls adapted to receive therebetween the lid hinge member when the lid is closed and with the lid hinge member nested within the intermediate hinge member, and when the lid is opened said lid hinge and intermediate hinge members are opened and extended beneath the lid, and a counterbalancing spring between the lid hinge member and the intermediate hinge member and having one end engaging the lid hinge member and the other end the intermediate hinge member for spring-biasing said last mentioned members to open, extended position whereby the lid is maintained counterbalanced in partially or fully open position and moved forwardly and inwardly from the chest hinge member as the lid is raised to open position.
